JAMES PATERSON, ASSR. ETC.,
DESIGN FOR A FLOOR CLOTH PATTERN.

James Paterson
by his Attr
Norman Austin

United States Patent Office.

JAMES PATERSON, OF ELIZABETH, ASSIGNOR TO R. H. AND B. C. REEVE,
OF CAMDEN, NEW JERSEY.

Design No. 4,007, dated May 3, 1870.

DESIGN FOR A FLOOR-CLOTH PATTERN.

The Schedule referred to in these Letters Patent and making part of the same.

I, JAMES PATERSON, of Elizabeth, county of Union, State of New Jersey, have invented or produced a new and original Design for a Floor-Cloth Pattern, of which the following is a specification.

The figure in the accompanying drawing represents sufficient of a floor-cloth to illustrate my design, which consists of an arrangement of square or diamond-shaped figures, A and B, and eight-sided figures, C, the latter forming the ground-work of the pattern, and being, in the present instance, spotted and lined in imitation of granite.

The figures A, which are formed between the long sides *a* of the surrounding figures C, are ornamented, by lines and shading, in imitation of marble.

The interiors of the figures B, which are also sur-

rounded by and formed between the figures C of the ground-work, are occupied by radial ornaments, *b*, clearly represented in the drawing.

Irrespective of the colors employed, I claim—

The design for a floor-cloth pattern, substantially as described, and as illustrated in and by the accompanying drawing.

In testimony whereof I have signed my name to this specification in the presence of two subscribing witnesses.

JAS. PATERSON.

Witnesses:

JOSEPH WHELEN,
JOHN NOE.
